SCOTCH BLOCK

Clifford C. Bradbury, Glencoe, Ill., assignor to
 Hayes Track Appliance Company, Richmond,
 Ind., a corporation of Indiana

Application May 16, 1938, Serial No. 208,139

15 Claims. (Cl. 104—259)

The present invention is directed to the improvement of car wheel stops of the type commonly known as Scotch blocks or the like, used on railway tracks. It is directed particularly to 5 Scotch blocks of the type disclosed in the Hayes Patent No. 1,801,917 assigned to the assignee of the present invention, which are slidably mounted upon rails and are provided with portions extending below the base of the rail into the 10 plane of the rail supporting ties for transmission of the shock of impact to the rail bed.

Scotch blocks constructed in accordance with the disclosure of the Hayes patent provide a cushion stop for the car wheels. This results 15 from the fact that the force of the car wheel impact is transmitted to and effects a slight movement of the ties in the rail bed. It is this slight movement that provides a cushion-like shock absorbing resistance which minimizes damage to 20 either the cars or rails. The blocks are applicable to rails without the necessity of drilling either the blocks or the rails and are designed for application to rails of different sizes.

A primary object of the present invention is to 25 provide a Scotch block that may be applied readily to rails of different sizes and which is adapted to limit movement of the car by effecting relative movement between the rail and tie in the plane of the rail to separate the two upon 30 car wheel impact.

A further object of the invention is to provide 35 a Scotch block adapted not only to effect relative movement between the rail and tie in the plane of the rail under car wheel impact but also to move the rail securing spikes sidewise as the block is gradually moved along the rail under successive impacts.

A further object of the invention is to provide 40 a new and improved Scotch block adapted not only to move the spikes sidewise but also downward, whereby the blocks may be used in connection with rails supported upon steel plates through which the spikes extend into the tie.

A further object of the invention is to provide 45 a Scotch block of the type described in which the means for effecting relative movement between the rail and tie and movement of the spike is constructed as an integral part of the block.

A further object of the invention is the provision 50 of attachments constructed separately from the blocks for mounting upon portions of the rails and contact by the blocks and which are adapted to effect relative movement between the rails and ties in the plane of the former and,

likewise, if desired, to drive the rail-securing spikes sidewise and downward as the attachment is moved by the stop under successive car wheel impacts.

Other objects and advantages of the invention 5 will become apparent from the ensuing description, in the course of which reference is had to the accompanying drawings, in which:

Fig. 1 is a side elevation of a single Scotch block and attachments mounted on a rail; 10

Fig. 2 is a top plan view, partially in section, of the apparatus shown in Fig. 1;

Fig. 3 is a partial rear elevation of the apparatus shown in the preceding figures. This view 15 may also be considered as a transverse cross-sectional view taken on the line 3—3 of Fig. 1;

Fig. 4 is a partial side elevation of a modified form of attachment;

Fig. 5 is a view similar to Fig. 3 of the apparatus shown in Fig. 4; 20

Fig. 6 is a side elevation of a modified form of Scotch block in which the means for effecting relative movement between the rail and tie is formed as an integral part of the block; and 25

Fig. 7 is a transverse sectional view taken along the line 7—7 of Fig. 6.

Referring first to Figs. 1 to 3 inclusive, the Scotch block indicated generally by reference numeral 10 may be seen to comprise a pair of plates 12 which are reverse duplicates of each other. They are secured together at their front ends and spread divergently apart at their rear ends thereby to form a tapered structure. The forward ends are secured together by suitable means as by welding them to a plurality of variously shaped spacing blocks 14, 16, 18, 20, 22 and 24 placed between the plates at suitable places as clearly indicated in Fig. 1. Additional spacing blocks may be utilized if desired. The forward ends of the plates are seated upon the rail head and the spaced apart rear ends are welded to an inverted U-shaped rail saddle 26 adapted to seat upon the rail head and extend, preferably but not necessarily, well below the base of the rail into the plane of the ties 28 upon which the rail 30 is mounted. The rail is shown seated upon steel plates 32 provided with four apertures through which the rail-securing spikes 34 are driven into the ties. 35

The rear end of the saddle is provided with a relatively wide flange 36 to give it greater strength and to distribute the force of the car wheel impact over a greater portion of the front faces 38 of the pair of attachments 40 which 40

55

are provided for the purpose of effecting relative movement of the rail and ties as the block is gradually moved under successive car wheel impacts. The construction of the attachments and 5 their mode of operation will be described in greater detail hereinafter.

The saddle 26 provides a means for centering the rear end of the Scotch block upon the rail and the downwardly extending portions thereof 10 are spaced far enough apart so that the saddle may be fitted over the largest size rails for which the block is designed.

The front or abutment end of the block 10 is centered upon the rail by a pair of eccentrically 15 bored centering blocks 42 removably mounted upon downwardly extending pins 44 by means of cotter pins 46. The pins 44 are formed integrally with blocks 48 welded or otherwise suitably secured to the outer surfaces of the plates 12. 20 The described construction of the front end centering means provides an easy means for centering the front end as centering can be accomplished simply by changing the angular positions of the blocks so that they always engage the 25 sides of the rail head.

The wheel abutment 50 is formed, as may be noted from Fig. 2, with a width greater than the combined width of the plates 12 by cutting the plates backward from their line of contact, 30 i. e., the line from which their divergence commences and which passes through the upper and lower points of contact of the plates. This construction eliminates all undesired stresses in the plate and provides an abutment of a width 35 sufficient to engage a considerable portion of the car wheel and at the same time permits the use of relatively thin plates. The abutment has a curvature corresponding to the contour of the car wheel and the block itself has a height substantially equal to the distance the car wheel axle 40 extends above the rail.

The front or abutment end of the block is clamped to the rail by non-clamping means indicated generally by reference numeral 52. This 45 clamping means comprises a looped structure adjustably supported from the plates by a pin 54 apertured at its end and extending through and welded to both plates. The spacing block 24 maintains the plates 12 a predetermined distance apart at the place where the pin 54 goes through the latter and also serves as a guide for the pin.

The clamping means itself consists of a pair of parallel bolts 56 extending vertically through 55 the apertures in the pin 54 and secured together at their lower ends by a cylindrical cross bar 58 welded thereto. Nuts 60 are threaded to the upper ends of the bolts and provide a means for drawing the cross bar 58 into engagement 60 with the under sides of rails of different size. The cross bar 58 is forced to travel in unison with the blocks by means of a pair of eye-bars 61 provided to prevent binding of the cross bar against the lower surface of the base of the rail. To 65 accomplish this, the bolts 56 pass through eyes 62 of the eye-bars and offset portions 64 of the latter are hooked through apertures at the lower ends of the divergent plates 12.

Returning now to a detailed description of the 70 attachment 40 which forms the principal feature of the present invention, it may be seen that this attachment may be divided more or less arbitrarily into three portions: The first, and most important, is the rear portion comprising a 75 pair of angularly disposed tapered surfaces 70

and 72 adapted respectively to drive the spikes 34 sidewise and to effect relative movement between the rail and the tie in the plane of the former whereby the rail and tie are separated. The attachments also comprise an intermediate 5 portion 74 of relatively narrow section lying above the flange of the rail and providing grooves 76 to permit the insertion of the offset portions 64 of the eye-bars 61. The rear ends of the attachments constitute the third portion. The 10 third portion is provided with downwardly extending projections 78 through which extends a bolt 80 by means of which the attachments are held in spaced relation to each other and are drawn into relatively close relationship to the rail 15 flange.

The attachments are supported upon the flanges of the rail and it may be seen that they are provided with tapered longitudinal laterally extending grooves 82 whose surfaces are adapted 20 to engage the top and bottom surfaces of the rail flanges. The grooves are dimensioned so that the attachments may be placed upon flanges of various sizes. In the embodiment illustrated, the attachments are shown mounted upon a rail 25 of large size, and because of the thickness of the flange, the attachments do not extend clear to the web of the rail as they would when mounted upon a rail of smaller size.

In order to make certain that the initial movement of the attachments under car wheel impact will effect a separation of the rail from the tie, the forward end of the attachment is made relatively pointed and narrow as indicated by reference numeral 83. The portion 83, which is 35 wedge-like in shape, is adapted to enter between the bottom of the rail and the plates 32 and is effective to force these apart, thereby drawing the spikes 34 upwardly from the tie. Upon further movement of the attachment the forward 40 pointed portion 84, also wedge-like in shape, which lies above the flange is effective to move the spikes sidewise so that they will not materially impede the gradual forward motion of the stop. 45

When applied to small sized rails the attachments are displaced toward the web of the rail, while the position of the saddle remains fixed. The over-all width of the attachment, therefore, should be sufficient to drive the spikes outward 50 beyond the blocks even when mounted upon rails of smallest size. In similar manner, on small rails the saddle 26 is displaced downwardly with respect to the attachments and in order to provide proper operation, the depth of the attachments likewise is so dimensioned that the ties never impinge the saddle or other parts of the stop.

It should be understood also that the tapered 60 surface 70 should extend from a point well toward the rail flange in order to avoid the danger of the point thereof striking the spike.

When it is desired to install a Scotch block of the type described in detail above, the two attachments 40 are first positioned upon the flanges 65 of a rail. Thereafter the bolt 80 is passed through the forward ends thereof and the two attachments are drawn fairly close to the flange but not so close as materially to impede movement of the attachments along the flange under car wheel impact. Thereafter, the block 10 is mounted upon the rail with the forward end seated thereon so that the saddle 26 straddles the rail and the narrow portion 74 of the attachment 40. The eye-bars 61 are then placed in position with 75

the offset portion 64 thereof hooked in the openings 76, and finally the U-shaped clamp is attached to the eye-bars 61 and the pins 54, slidably to clamp the forward end of the stop upon the rail.

A Scotch block is similarly mounted upon the other rail and when the two are in place, the apparatus is ready for operation. Whenever a car strikes the block, the force of the impact is transmitted by the block to the attachment. This force tends to cause a rearward motion of the block and attachment and this in turn is effective first to effect a separation of the rail from the tie and thereafter to effect a further separation of the rail and tie and simultaneously therewith to drive the spikes 34 sidewise. This movement of the attachment, it should be understood, is relatively gradual, because the force of the impact is absorbed to a certain extent by the tie and the ballast. Furthermore, the weight of the car itself is utilized in stopping the car because of the fact that this weight tends to oppose the separation of the rail from the tie. Another advantage of the described arrangement resides in the fact that if the stop moves past one tie, because of long continued use, it will operate in the same manner on the next tie. The whole stop thus will continue to move past successive ties until it is desired to return it to its initial position.

In the modified form of the invention as illustrated in Figs. 4 and 5, the attachment is adapted not only to effect relative movement between the rail and tie and sidewise displacement of the spikes, but also to drive the spikes downward after they have been moved sidewise a predetermined distance. This type of attachment is particularly advantageous where steel plates 32 are used, because it is not necessary to drive the spikes sidewise as far as in the previously described form.

The modified form of attachment is indicated generally by reference numeral 90. It comprises a horizontally tapered surface 92 and a vertically tapered surface 94 corresponding to the surfaces 70 and 72 of the previously described embodiment. The surface 94 which lies below the rail flange terminates in a rear narrow portion 96, while the surface 92 terminates in a narrow and pointed portion 98 corresponding respectively to the portions 83 and 84 of the previously described modification. The attachments are provided with longitudinal grooves 100 whereby they may be and are supported by the flanges of the rail and have downwardly extending curved surfaces 102 by means of which the spikes are driven downwardly below the scotch blocks by the movement of the attachments under successive car wheel impacts. The spikes are first driven sidewise by the forward portions 98 of the attachments located above the rail flange until they are moved sidewise beyond the flange. Thereafter the spikes are driven downward in an uninterrupted manner by the portions 102. It should be observed that the upper ends 104 of the surfaces 102 should be at a height sufficient readily to receive the heads of the spikes 34.

When the attachment and wheel stop of the present modification have been installed, the initial movement of the stop and attachments results in a relative movement between the rail and tie in the plane of the rail to effect separation of the rail and tie just as in the previously described embodiment. After the two have been

separated a predetermined distance, the portion 98 of the attachment effects sidewise movement of the spikes, and finally after the spikes have been moved sidewise a predetermined amount, the surface 102 drives the spikes down below the level of the block. While not illustrated, it may be noted that the attachments 90 need not be made as wide as the attachments 40 of the previously described embodiment, because the spike does not have to be driven sidewise beyond the outermost points of the stop. As pointed out above, the advantage of this construction resides in the fact that there is no tendency to shear the spike by the considerable sidewise movement thereof.

The advantages of the present invention are realizable in blocks of different construction in which the attachment is made integral with the block. A device of this sort has been illustrated in Figs. 6 and 7. In this modification, the Scotch block comprises a pair of complementary plates 110 and 112 having their forward upper ends curved to form a wheel abutment 114. The plates are provided with intermediate outwardly disposed sections 115 adapted to fit over the largest size of rail to which the block is to be attached, while the lower extremities of the plates are provided with laterally extending grooves 116 adapted to fit over the flanges of the rail 30. The plates are held together by a plurality of bolts 118 located near the top of the block, near the surface of the rail head and below the base of the rail. The bolts located at the two first mentioned places pass through spacers 120, which are of a size dependent upon the size of the rail. The bolts 118 below the base of the rail are drawn only so tightly as to permit relatively free movement of the block along the rail under car wheel impact.

The rear ends of the blocks are constructed in a manner similar to the attachments 90 of the modification shown in Figs. 4 and 5. However, the various angularly disposed surfaces of this attachment are formed integrally with the two plates forming the Scotch block. The bottom surfaces of the plates are tapered as indicated at 122, this taper being relatively gradual and extending from the lower surface of the rail to a point below the lowermost bolt 118. The rear end of the portion of the plate below the rail flange terminates in a relatively narrow pointed end 124 adapted to effect separation of the rail and tie. A portion of each plate is provided with a vertical surface 126, lying above the rail flange and terminating slightly forward of end 124, for the purpose of driving the spikes sidewise, while the curved surface 128, corresponding to the surface 102 of the embodiment shown in Figs. 4 and 5, drives the spikes below the rail flange and block.

From the above detailed description, it should be apparent to those skilled in the art, that the rail is separated from the ties by the tapered surface 122, and that the spikes 34 are driven sidewise and finally downward by the surfaces 126 and 128 as the Scotch block moves progressively rearwardly under successive car wheel impacts.

The various modifications embodying the present invention have been illustrated in order to set forth the details of applicant's invention. From these modifications it should be apparent to those skilled in the art that the invention is susceptible of change by those skilled in the art. For this reason it is contemplated that the embodiments that have been described are not to

be considered as limitative in any way and that the invention is limited only by the claims.

What I claim as new and desire to secure by United States Letters Patent is as follows:

- 5 1. A wheel stop adapted slidably to be mounted upon a rail, including in combination, a car wheel abutment structure upstanding in the plane of the rail and having a height substantially equal to the distance the car wheel axle 10 extends above the rail, said structure having a wedge-like extension below and located adjacent the base of the rail adapted to enter between the rail and tie to effect separation of the rail and tie for resisting movement of the 15 stop under car wheel impact.
2. A wheel stop adapted slidably to be mounted upon a rail, including in combination, a car wheel abutment structure upstanding in the plane of the rail and having a height substantially equal to the distance the car wheel axle 20 extends above the rail, and means including structure supported by the rail flanges having a wedge-like extension below and located adjacent the base of the rail, said structure being 25 separable from but in abutting engagement with the stop, and said extension being effective to enter between the tie and rail to cause separation of the rail and tie for resisting movement of the stop under car wheel impact.
- 30 3. A wheel stop adapted slidably to be mounted upon a rail, including in combination, a car wheel abutment structure upstanding in the plane of the rail and having a height substantially equal to the distance the car wheel axle 35 extends above the rail, said structure having an extension formed integrally therewith and having a wedge-like portion extending below and located adjacent the base of the rail adapted to enter between the rail and tie to effect 40 separation of the rail and tie for resisting movement of the stop under car wheel impact.
4. A wheel stop adapted slidably to be mounted upon a rail fastened to ties by spikes, including in combination, a car wheel abutment 45 structure upstanding in the plane of the rail and having a width greater than the rail, and a wedge-like extension below and located adjacent the base of the rail adapted to enter between the rail and tie to effect separation of the rail and tie for resisting movement of the stop under car wheel impact, said extension having a pair of laterally diverging surfaces located 50 above the rail flanges for driving the spikes sidewise away from the rail whereby the spikes will not substantially impede forward movement of the stop.
5. A wheel stop adapted slidably to be mounted upon a rail fastened to ties by spikes, including in combination, a car wheel abutment structure upstanding in the plane of the rail and having a width greater than the rail, and a wedge-like extension below and located adjacent the base of the rail adapted to enter between the rail and tie to effect separation of the rail and tie for resisting movement of the stop under car wheel impacts, said extension having a pair of laterally diverging surfaces located 60 above the rail flanges for driving the spikes sidewise away from the rail and having a pair of downwardly inclined surfaces associated with the last mentioned surfaces for driving the spikes downward whereby the spikes will not substantially impede the forward movement of the stop.

6. A wheel stop adapted slidably to be mounted upon a rail seated upon a plate and secured to a tie by spikes passing through the plate, including in combination, a car wheel abutment upstanding in the plane of the rail and having a width greater than the rail, and a wedge-like extension below and located adjacent the base of the rail adapted to enter between the rail and plate to effect separation of the rail and tie for resisting movement of the stop under car wheel impacts, said extension having a pair of laterally diverging surfaces located above the rail flanges for driving the spikes sidewise away from the rail and having a pair of downwardly inclined surfaces associated with the last mentioned surfaces for driving the spikes downward below the stop as the latter stop is moved forward, whereby the extension will impede but not prevent movement of the stop and will not shear off the spikes when it is moved by the stop.

7. An attachment for use with a wheel stop adapted to be mounted upon a rail and to slide therealong under car wheel impact, comprising a member adapted to be placed in front of the stop for engagement with and movement thereby and supported by the flange of the rail, said member being provided with a plurality of angularly disposed wedge-like structures defining surfaces for effecting, first, relative movement between the rail and its supporting tie to separate the two by entering between the rail and tie and, second, sidewise movement of the spike securing the rail to the tie and finally, downward movement of the spike.

8. An attachment for use with a wheel stop adapted to be mounted upon a rail and to slide therealong under car wheel impact, comprising a member adapted to be placed in front of the stop for engagement with and movement thereby and supported by a flange of the rail, said member being provided with a first surface lying substantially in a vertical plane and tapered so as to extend from between the web and outer edge of the flange of the rail beyond the flange for driving the spikes securing the rail to the tie sidewise as the stop moves the attachment forward, said member being also provided with a second surface tapered vertically so as to enter between the rail and tie to effect separation of the rail and tie as the attachment moves forward.

9. An attachment for use with a wheel stop adapted to be mounted upon a rail and to slide therealong under car wheel impact, comprising a member adapted to be placed in front of the stop for engagement with and movement thereby and supported by a flange of the rail, said member being provided with a first surface lying substantially in a vertical plane and tapered so as to extend from a point between the web and outer edge of the flange of the rail beyond the outer edge for driving the spikes securing the rail to a tie sidewise as the stop moves the attachment forward, said member being provided with a second surface tapered vertically and having a relatively thin and narrow forward end adapted to enter between the rail and tie for effecting separation of the rail and tie as the attachment moves forward, said member being provided also with a third surface tapered vertically and arranged to drive the spikes downward after the first surface has driven them sidewise a predetermined distance.

10. A scotch block having at one end a car wheel abutment upstanding in the plane of the rail and adapted to slide along the rail under car wheel impact, said block having dependent structure straddling the rail and extending below the bottom of the rail whereby the stop may be slidably clamped to the rail and having further dependent structure extending below the bottom of the rail at the end opposite the abutment, and 5 means including structure having a wedge-like portion supported by the rail for contact by said last mentioned structure and separable from the block, adapted to enter between the rail and tie to effect separation of the rail and tie for absorbing the shock of car wheel impact. 10
11. A scotch block having at one end a car wheel abutment upstanding in the plane of the rail and adapted to slide along the rail under car wheel impact, said block having dependent structure straddling the rail and extending below the bottom of the rail whereby the stop may be slidably clamped to the rail and having further dependent structure extending below the bottom of the rail at the end opposite the abutment, and 15 means supported by the rail for contact by said last mentioned structure and separable from the block, adapted to effect separation of the rail and tie for absorbing the shock of car wheel impact, said last mentioned means comprising a pair of attachments supported by the rail flanges and provided with a plurality of angularly disposed wedge-like structure defining surfaces adapted to effect separation of the rail from the tie by entering between the rail and tie and to drive 20 the rail spikes away from the dependent structure of the rail. 25
12. A scotch block having at one end a car wheel abutment upstanding in the plane of the rail and adapted to slide along the rail under car wheel impact, said block having dependent structures straddling the rail and extending below the bottom of the rail whereby the stop may be slidably clamped to the rail, and means defining wedge-like structure below the rail supported by the rail for contact by the stop and separable therefrom adapted to enter between the rail and tie to effect separation of the rail and tie for absorbing the shock of car wheel impact. 30
13. A scotch block having at one end a car wheel abutment upstanding in the plane of the rail and adapted to slide along the rail under car wheel impact, said block having dependent structure straddling the rail and extending below the bottom of the rail, means extending below 35
- and across the bottom of the rail and cooperating with said structure for slidably clamping said stop to different sized rails, said block having further dependent structure at the end opposite the abutment extending at least some distance below different sized rail heads, and means supported by the rail for contact by said last mentioned structure and separable from the block adapted to effect separation of the rail and tie, said last mentioned means comprising a pair of attachments provided with longitudinal grooves adapted to contact the upper and lower surfaces of flanges of different sized rails, with a plurality of angularly disposed surfaces adapted to enter between the rail and tie for effecting separation 40 of the rail from the tie with a pair of diverging surfaces located above the rail flanges for driving the rail spikes away from the dependent structure of the stop, with a relatively narrow intermediate portion adapted to fit between the further dependent structure and webs of different sized rails above the flanges and with a dependent portion extending below the bottom of the rail whereby the pair of attachments may be slidably clamped to the rail flanges. 45
14. A device of the class described comprising two complementary upright members having their front ends shaped to conform to a car wheel and having lower portions adapted to surround and to be slidably clamped to a rail, and integral rear portions provided with angularly disposed wedge-like structure defining surfaces the pointed portions of which lie adjacent the rail base for entry between the rail and tie adapted to effect separation of the rail and its supporting tie, said rear portions being provided also with a pair of diverging surfaces located above the rail flanges to drive rail securing spikes sidewise. 50
15. A device of the class described comprising two complementary upright members having their front ends shaped to conform to a car wheel and having lower portions adapted to surround and to be slidably clamped to the rail flanges, and integral rear portions provided with angularly disposed surfaces defining wedge-like structure adjacent the base of the rail adapted to enter between the rail and tie to effect separation of the rail and its supporting tie and other angularly disposed surfaces defining wedge-like structure adjacent the rail web and alongside the rail to drive the rail securing spikes sidewise and downward. 55

CLIFFORD C. BRADBURY.
